LOUNGE CHAIR

Leo Jiranek, Old Greenwich, Conn., assignor to Heywood-Wakefield Company, Gardner, Mass., a corporation of Massachusetts

Application September 10, 1956, Serial No. 42,879

Term of patent 7 years

(Cl. D15—11)

Fig. 1 is a perspective view of a lounge chair showing my new design;

Fig. 2 is a perspective rear view thereof on a scale slightly smaller than the scale of Fig. 1;

Fig. 3 is a fragmentary detail view on the line 3—3 of Fig. 1, but on a scale slightly larger than that of Fig. 1;

Fig. 4 is a fragmentary view in elevation on the line 4—4 of Fig. 3, and

Fig. 5 is a perspective view of one of the chair arms, substantially on the scale of Figs. 3 and 4.

I claim:

The ornamental design for a lounge chair, substantially as shown.
